UNITED STATES PATENT OFFICE.

ROBERT T. HAZELTON, OF CINCINNATI, OHIO, ASSIGNOR TO THE CINCINNATI SHAPER COMPANY, OF CINCINNATI, OHIO, A CORPORATION OF OHIO.

STROKE INDICATOR.

Application filed July 25, 1924. Serial No. 728,275.

To all whom it may concern:

Be it known that I, ROBERT T. HAZELTON, a citizen of the United States, and residing at Cincinnati, in the county of Hamilton 5 and State of Ohio, have invented a new and useful Improvement in Stroke Indicators, of which the following specification is a full disclosure.

This invention relates generally to improvements in metal working machines and is shown herein as applied to a shaper of the oscillating link type, and the invention particularly relates to indicator mechanism for indicating the length of stroke to which 15 the shaper ram is adjusted and providing a dial reading for making a ram stroke length setting or adjustment.

An object of the invention is to provide simple and positively operable means for 20 indicating the stroke length of the ram of a shaper and whereby the changes in stroke length are made visually evident to the operator.

A further object is the provision of a 25 stroke adjusting mechanism and a stroke indicating device operative through ram stroke adjusting means or mechanism of the machine.

Another object is to mount the dial at 30 such an angle as will permit the most convenient observation and reading by the operator at a position in making an adjustment of the ram, thus the dial member of the device is placed at an angle to both 35 horizontal and vertical planes, for this purpose.

Important features of the invention include a sleeve translatable by the stroke adjusting shaft of the stroke adjusting 40 mechanism, the sleeve having circumferential rack teeth directly engaged with a spur or spiral gear at one end of a dial shaft upon the other end of which is mounted a graduated disk the graduations of which 45 are registerable with a mark upon the machine frame.

Other objects and features and certain 50 advantages will be pointed out in the description of the drawing forming a part of this specification, in which drawing:

Figure 1 is a vertical transverse section showing the application of my device to a shaper.

Figure 2 is an end elevation partly in 55 section showing the relation of the dial disk

to the casing, and of the dial shaft gear to the sleeve translatable upon and by the spindle.

Figure 3 is a sectional elevation of the sleeve. 60

Figure 4 is a face view of the dial.

Figure 5 is a sectional elevation of the dial and dial shaft assembled.

Referring to the drawings, the numeral 1 indicates the frame of the machine which is 65 mounted on a suitable base, the upper side of the frame being provided with the usual dove-tail guideway within which the ram 3 reciprocates. The forward end of the ram is equipped with the ordinary tool 70 holder, not shown herein. The ram is reciprocable by a pitman or oscillating link 4 which at its lower end is provided with a hub through which a suitable pivot rod 5 is engaged, the rod having its opposite ends 75 supported in bearings formed in opposite side walls of the main frame. The upper end of the pitman is suitably connected with the ram by a link 6, the connection of the link with the ram not herein being shown. 80 Moreover, the link may be connected to any other form of reciprocatory member corresponding to the ram shown herein and the connection may be made in any suitable manner. 85

The pitman is in the form of a casting and provides a longitudinally recessed portion open at one side, providing opposing parallel walls as ways or guides for a crank pin slide block 10. The slide block is engaged 90 by a crank pin 11 adjustably secured and projecting from a gear 12. The gear 12 has a tubular counterturned portion or hub 13 extending from one side and journaled in a bearing sleeve 14 which sleeve is in 95 turn engaged within and through a bearing opening at one side of the main frame. The sleeve is suitably attached in position to the main frame by screws. The inner face of the crank gear is provided with a radial 100 guideway 15 formed by a pair of spaced ribs projecting from the side of said gear, the ribs terminating in a web or lug 16 forming a bearing for supporting and journaling one end of a diametrically disposed 105 screw shaft 18 which is disposed centrally between the ribs. The screw shaft 18 is rotatable in its bearing, and is held from longitudinal motion by collars 19 pinned to the screw shaft at the outer end and abut- 110

ting one side of the lug 16 and by a bevel gear 20 pinned to the screw shaft at the opposite side of the lug.

The screw rod has threaded engagement 5 as at 21 with the crank pin 11, which pin has a nut or head portion 25 as a slide block engaged within the guideway 15 of the crank gear. As before indicated the crank pin journals within the block and is slideable 10 in the pitman guideway. When the screw 18 is rotated the crank pin and slide-block 10 are brought in directions toward or away from the gear axis, thus obtaining shorter or longer throw of the pitman.

15 For adjusting the throw of the crank pin the screw 18 is revolved by means of the bevel pinion 20 meshing with a pinion 27 journaled on a stub shaft carried by the gear 12 adjacent its center, and this pinion 20 has, in addition to bevel teeth, spur teeth meshing with corresponding spur teeth 30 on the end of a spindle 32 which is concentrically journaled within the hub 13 and extends outwardly as shown.

25 The forward end of the spindle is journaled in a hub cap 35 secured to the outer end of the hub 13 of the crank gear. The hub cap 35 has an elongated hub extension upon which a crank member 36 is engaged 30 and rigidly fixed to the hub cap and hub end of the crank gear by screws or other fastening means whereby the hub cap and crank member 36 are unitarily combined with the crank gear and rotative therewith. 35 The crank member 36 in the instance shown is represented as an eccentric collar peripherally circumferentially grooved to provide for a varying crank motion transmitting range for the carriage or table feeding 40 mechanism of the machine tool, representing an invention made the subject matter of a separate application by me of even date herewith.

The spindle, intermediate of its length 45 has a conical portion 38 frictionally engaging with a corresponding conical seat 39 in the hub cap 35 at the inner side thereof, for normally binding the spindle against rotation to avoid disturbing a crank throw setting, which is effected by independently rotating the spindle. The spindle is held against the seat in the hub cap under pressure by a spring 40 about the spindle between an inner wall of the crank gear hub 55 and an annular flange on the spindle. To release the spindle from its binding engagement with the hub cap the spindle is depressed inwardly, a slight longitudinal motion only being required which is applied by 60 the operator.

The outer end of the spindle beyond the conical bearing portion is threaded as at 41 and squared at its extremity to provide a wrench socket crank receiving head 42 for 65 rotating the spindle to make a crank throw

adjustment. The crank throw adjustment mechanism above described while illustrative of a preferred form of construction may be representative of any conventional form in the present commercial shapers 70 characteristic to the employment of a rotary spindle extending from the axis of the crank gear for making a crank throw adjustment and to which my improved indicator mechanism is applicable. 75

The indicator mechanism comprises a sleeve or tubular rack element 45 having its bore 46 screw-threaded and engaged with the corresponding threaded portion 41 of the spindle, and the sleeve exteriorly is circumferentially grooved, as shown in Fig. 3 in detail, providing rack teeth 47. The sleeve is splined as at 49 within the bore into the end of the hub 13 of the cap 35, and therefore rotative with the crank gear, and translatable longitudinally upon the spindle when the spindle is independently rotated for a crank throw adjustment. The teeth of the rack sleeve are engaged with the spiral gear 50 formed at the lower end of

80 the shaft 51 which is journaled in a bearing in the frame, or in a cap plate 55 removably attached to the frame 14. At the upper end of this shaft is fixed a disk 52 in the form of a dial upon the periphery of which are 85 graduations 53 registerable with the indicator mark 54 upon indicator face of the casing 55. The upper end of the shaft is turned to provide a conical surface with

90 which is engaged the corresponding conical opening of the disk, a clamping screw being provided to force the parts into frictional binding engagement, see Fig. 5. The shaft 51 and dial 52 are disposed at an angle so 95 that the graduations are fully visible from the operator's position in making a crank throw adjustment. In an adjustment of the crank or crank pin 11 by the rotation of the spindle 32 the sleeve is fed inwardly or outwardly, according to the direction of 100 spindle rotation as may be required, and this translative movement imparts rotative motion to the rack gear 50, shaft 51 and dial 52 in a corresponding degree relative to the longitudinal movement of the rack sleeve 105 upon the spindle.

This indicator mechanism is very simple in construction, and efficient with a very limited number of parts and under an arrangement in which there is no perceptible amount of lost motion.

Having described my invention, I claim:

1. In a device of the class described, a crank gear having a crank pin adjustably mounted thereon a stroke-adjusting mechanism including a rotatable spindle journaled within said crank gear, a sleeve independently translatable non-rotatably mounted within said crank gear, having threaded connection with said spindle and having rack teeth

- thereon, and a rotatably mounted dial-shaft having a gear at one end in mesh with said rack teeth and having a graduated disk rotatable therewith for visually indicating the 5 degrees of stroke adjustment when said spindle is independently rotated.
2. In a device of the class described a crank gear having a crank pin adjustably mounted thereon, a stroke-adjusting mechanism including a rotatable stroke-adjusting shaft journaled within said crank gear, a sleeve independently translatable non-rotatably mounted within said crank gear and having threaded connection with said shaft, 10 said sleeve having circumferential rack teeth, and a rotatable dial-shaft having a gear at one end in mesh with said rack teeth and having a graduated disk at the other end for indicating the degree of stroke 15 adjustment when said adjusting shaft is rotated for a stroke adjusting operation.
3. In a device of the class described, a support, a driving member rotatable therein having an adjustable crank therein, means 20 for radially adjusting said crank including a spindle rotatably supported in said driving member, a sleeve translatable non-rotatably mounted upon said driving member having circumferential rack teeth, and a 25 dial-shaft having a gear thereon in mesh with said rack teeth and having a graduated disk for visually indicating the degree of crank pin adjustment when said spindle is independently rotated.
- 30 4. In a device of the class described, a driving member rotatably mounted, a crank pin adjustable thereon, means for adjusting said crank pin including a rotatable member, adapted for non-rotation and rotation relative to said driving member, respectively, 35 to adjust said crank pin and to maintain the adjustment, a sleeve in threaded engagement with said shaft having circumferential spur teeth and splined to said driving member, and a dial-shaft having a gear in mesh with said spur teeth adapted to be rotated by said sleeve when the same is translated by an adjusting rotation of the spindle, 40 said dial-shaft having a dial member having visual graduations thereon for indicating the 45 degree of pin adjustment.
5. In a device of the character described, a rotatably mounted crank gear having a hub, a crank adjustable upon said gear, a 50 spindle concentrically journaled within the gear hub in transmission connection with said crank for adjusting the same when rotated, a sleeve in threaded engagement with the spindle having circumferential 55 rack teeth and splined to said hub, and a dial-shaft independently journaled having
- a gear in mesh with the circumferential teeth of said sleeve and having a dial rotatable therewith for indicating the degree of crank pin adjustment when said spindle 60 is independently rotated.
6. In a device of the class described, a frame, a gear having a hub extension rotatable therein, a crank adjustable upon said gear, a terminally-threaded spindle concentrically journaled within said hub and transmittably connected with said crank for adjusting the same, a circumferential toothed sleeve engaged with the spindle threads and splined to the hub, and a dial-shaft independently rotatably mounted in said frame having a gear in mesh with a tooth of said spindle and having a graduated dial rotatable therewith and visible from the outer side of the frame for indicating the degree 70 of crank adjustment when said spindle is rotated.
7. In a machine tool of the character described, a frame, a crank gear within said frame, having a tubular hub journaled in 75 said frame, a radially adjustable crank upon the side of the gear, a spindle journaled within the hub transmittably connected with the crank for adjusting the same, a sleeve in threaded engagement with the spindle 80 having circumferential gear teeth and splined to said hub, and a dial-shaft independently rotatably mounted having a spur gear thereon in mesh with the teeth of said sleeve and having a graduated dial rotatable therewith and adapted for visually indicating the 85 degree of crank pin adjustment upon the gear when said spindle is rotated upon adjusting operation.
8. In a device of the class described, a frame, a crank gear having a hub extension rotatable therein, a crank radially adjustable upon said gear, a spindle concentrically journaled within the hub transmittably connected with said crank for adjusting the 90 same, a sleeve rotatable with and translatable relative to said hub in threaded connection with said spindle having circumferential spur teeth, said sleeve adapted to be fed longitudinally of the spindle when the 95 spindle is rotated for crank adjustment, and a dial-shaft rotatable in the frame having a gear in mesh with the spur teeth of the sleeve and having a dial rotatable therewith at the outside of the frame having graduations registerable with a mark on the frame 100 for indicating the degree of movement of the crank pin during adjusting rotation of the spindle.
- In witness whereof, I hereunto subscribe my name.

ROBERT T. HAZELTON.
